ARTICLE OF JEWELRY HAVING AN UNFURLABLE COVER

Robert Altman, Bronx, N.Y. (% Robert Altman Incorporated, 38 W. 48th St., New York, N.Y. 10036)
Filed Dec. 6, 1965, Ser. No. 512,579
13 Claims. (Cl. 58—88)

This invention relates to an article of jewelry having an unfurlable domed cover.

It is the primary object of my invention to provide an article of jewelry including a novel cover for a wrist watch, a miniature portrait or other display matter, the cover being characterized by a ring of petals which may be unfurled by the wearer in a manner imitative of the opening of a bud of a flower from a furled position blocking view of the wrist watch face, etc., to a position simulating an opened corolla that rings the face and exposes it to view.

It is a further object of my invention to provide an article of jewelry having an unfurlable domed cover of the character described wherein the cover is simple in construction, few in its number of parts and is so constructed that no mechanical-looking components can be observed.

It is a further object of my invention to provide an article of jewelry having an unfurlable domed cover of the character described which, when the cover is closed, has the appearance of a highly decorative and interesting nature-simulative article of jewelry and which, when opened, reveals a previously concealed watch or other display matter.

Other objects of my invention in part will be obvious and in part will become apparent to the reader in the following description.

My invention accordingly consists in the features of construction, combinations of elements and arrangements of parts which will be exemplified in the article of jewelry hereinafter described and of which the scope of application will be indicated in the appended claims.

In the accompanying drawings in which is shown one of the various possible embodiments of my invention,

FIG. 1 is a top plan view of my article of jewelry having an unfurlable cover, the cover being illustrated in closed condition;

FIG. 2 is an enlarged axial cross-sectional side view of the article of jewelry and illustrating in full lines the closed position and in dot-and-dash lines the open position of the petals of the cover;

FIG. 3 is a bottom plan view of the article of jewelry shown in FIG. 1;

FIG. 4 is a transverse cross-sectional view of three neighboring petals of the cover;

FIG. 5 is a fragmentary interior elevational developed view of a few petals of the cover;

FIG. 6 is a greatly enlarged view of a stamen-simulating jewel mounting assembly used in connection with my article of jewelry; and

FIG. 7 is a view similar to FIG. 1 but illustrating the cover in open condition.

In general, and in accordance with the teaching of my invention, I provide an article of jewelry having an unfurlable domed cover. Said article of jewelry may include within its interior a watch, a miniature portrait, or any other decorative or display matter. As will be seen, the wearer of my article of jewelry or any other person in his immediate vicinity when looking at the article of jewelry when the cover is closed will only see a very decorative and interesting article having a general configuration fancifully simulating a tightly closed bud of a flower. However, the cover of my article of jewelry can be quickly and easily opened by the wearer so as to

2

form an encircling opened corolla that exposes to view the interior of the article, that is, the face of the watch, the portrait, or other display material housed therein. The cover in opening "unfurls" its petals in a manner quite like that of the petals of a flower bud expanding or moving apart. This unfurling movement is an appealing aspect of my cover, and carries forward the nature-imitative concept embodied therein.

The article of jewelry includes a frame on which the watch and the like are mounted and a ring of petals each separately hinged on the frame. The petals are successively marginally overlapping in a shingle-like fashion, that is, each petal has one of its edge portions located on the interior face of the adjacent edge portion of one of its immediately neighboring petals and has its other edge portion located on the exterior face of the adjacent edge portion of its other immediately neighboring petal. Each of the petals is hinged on the frame about an axis of rotation and the axes of rotation preferably lie in the same plane with each axis of rotation forming with the axes of rotation of its neighboring petals an interior angle of from between about 60° to less than 180°. In the preferred embodiment of my invention there are six petals symmetrically arranged so that the axis of rotation of each petal forms a 120° interior angle with the axes of rotation of its neighboring petals. Each petal is substantially spherically segmental or cup-shaped, i.e. externally bellied. When the cover is in its closed condition, the petals are inwardly inclined with their tips juxtaposed at the top center of the cover so as to define an essentially closed dome having a hollow interior. When the cover is open, the petals are swung out to a substantially erect or even outwardly inclined position with their tips spaced from one another and from the top center of the cover so that the petals form an open corolla. Each petal has one edge portion which in open condition of the cover urges the adjacent portion of the overlapping neighboring petal radially outwardly. A chain reaction is thus achieved initiating from the petal which is manually operated by the wearer of the article of jewelry and running a complete circle through the ring of petals until the petal immediately before the first operated petal is again reached. As has been said, the ring of petals in an open condition permits view of the interior of the article of jewelry. Spring means biases the ring of petals to their closed condition.

Referring now in detail to the drawings, the reference numeral 10 denotes an article of jewelry having an unfurlable domed bud-simulating cover incorporating my present invention. The domed cover will hereinafter be referred to by reference numeral 12.

The article of jewelry includes an annular substantially cylindrical frame 14 on which the several other components of my invention are mounted and which holds any display matter within the article of jewelry. In the embodiment of my invention which is illustrated in the drawings, the display matter constitutes a watch 16 which, as is conventional, includes a watch casing 18, a watch stem 20 protruding from the casing and a crystal 22 secured in the top of the casing 18. The frame 14 has an open top and an open bottom and is of sufficiently large internal diameter to allow for placement of the watch casing therein. The display matter may also be a cameo, portrait or gem. The article of jewelry may alternatively be mounted on a ring, chain, loop, pin or any mounting in which case the opening in the frame may be eliminated if desired. The frame has a lower rim or border 15 which defines a circle lying in a plane.

Means is provided to mount the watch 16 for selective rotation about an axis parallel to the plane of the border 15 so as to expedite winding of the watch stem and repair of the watch interior. If such means were not provided

and the watch fixed in place, the stem of the watch would have to be permanently exposed and might detract from the naturalistic bud-like appearance of the article of jewelry. Said mounting means includes a pair of diametrically aligned trunnions 24 having their exterior ends fixed to the frame 14 at diametrically opposed locations and having their interior ends rotatably seated in aligned apertures in the casing 18. The normal position of the watch is with the watch crystal 22 facing upwardly and, when the cover is open, exposed to view (see FIG. 7). The watch is retained in this position by a resilient wire loop 28 (FIG. 3) fixed to the bottom of the casing which grippingly engages a squat headed stud 30 dependent from the frame. The loop can be readily slipped off the stud 30 so that the watch may be turned about the trunnions 24 through approximately a 120° angle of rotation until a portion of the casing strikes a blocking portion of the frame. In this condition, the stem 20 is exposed from beneath the frame and can be wound. The crystal 22 may be removed at this time for the purpose of repair. The watch rotated through 90° is shown in dot-and-dash lines in FIG. 3. The watch may be counter-rotated back to its normal position as desired.

My article of jewelry, as illustrated in the drawings, is attached to a watch band. To this end, two outwardly extending arms 32, 34 attach diametrically opposed portions of the frame 14 to the proximate ends of a wrist watch band 36. Each of the arms and its connection to both the frame and to an end of the watch band are the same and only one needs be described. The arm 32 includes two laterally spaced inwardly extending fingers 38 and each of the fingers at its tip is in one piece with the frame at its lower periphery. The arm 32 further includes an outwardly opening box-shaped member 40 which is configured to receive an end of the watch band 36. The member 40 overlies the watch band end on its top, bottom, and both sides and a pintle 42 passes transversely through a sleeve 41 in the watch band end and through both sides 41a of the box-shaped member 40, thereby to retain said watch band end within the member. The arm 32 may also carry a row of upwardly extending settings 44 to hold a series of small gems 46.

The cover 12 of my article of jewelry, which is the highlight of my invention, is made up of a ring 48 of metal petals 50. Each of the petals 50 is the same and in a preferred embodiment of my invention six petals comprise the cover 12. The cover 12 when closed over the watch 16 is dome-shaped with a rather flattened peak, with a diameter greater than its height, and with a flat bottom defined by the lower periphery of the frame 14. Each of the petals 50 defines an equal part, i.e. 1/6 of the domed configuration of the closed cover and each petal is approximately spherically segmental, i.e. cup-shaped (externally bellied) with a radius of curvature emanating from the general vicinity of the center of the cover 12. Within the description just given, it will be appreciated that each of the petals may be further configured to enhance the outward appearance of the article of jewelry and to this end in the illustrated embodiment each petal 50 is formed to simulate a cup-shaped petal of a flower (see FIG. 5). Each petal includes a broad base 52, two opposed marginal portions 54, 56 having edges, respectively, 55, 57 and a tip 58. The outer surface and tip 58 of each petal may be chased to form veins that further create the illusion of a nature-imitative object.

Each petal has in one piece therewith and located below its base 52 a bearing 60 which is journaled on the lower periphery of the frame 14. The journaling, i.e. hinging, of each of the petals permits movement of each of the petals from an inwardly inclined closed position at which view of the watch 16 is blocked and at which the tips 58 of the petals are juxtaposed over the center top of the cover (see FIG. 1 and solid lines in FIG. 2) to an outward position at which the petals are spread apart, being approximately erect or even outwardly inclined, so

as to form an encircling corolla that permits view of the watch 16 and at which position the tips 58 of the petals are quite distant from one another and from the center of the cover (see cover in FIG. 7 and in dot-and-dash lines in FIG. 2).

The bearing 60 of each petal is flanked by a pair of spaced aligned mounts 62, said mounts being integral with the lower rim 15 of the frame 14. There is a pair of mounts 62 for each petal and the pairs of mounts are equidistantly and equiangularly spaced around the lower rim of the frame, defining a regular hexagon. A pin 64 rotatably passes through a central bore 65 (see FIG. 4) in each of the bearings 60 and has its ends fixed in the aligned bores in each of the flanking mounts 62, thereby enabling each petal to swing back and forth on the frame 14 about its associated pin. It will be noted that the axes of rotation of all of the petals on the frame lie parallel to the plane of the border 15. Further, the axis of rotation of each petal intersects and makes the same angle with the axis of rotation of its immediately adjacent petals and forms therewith an interior angle of from between 60° (for a cover of three petals) to less than 180° (for a cover of a large number of petals). In the symmetrical six petal embodiment shown in the drawings, there is a 120° interior angle between adjacent axes of rotation.

It will be observed that each petal, when the ring of petals opens, moves away from every other petal and outwardly from a line which is perpendicular to and passes through the center of the circle defined by the frame boundary 15.

The petals of the cover are hingedly located about the frame in what may be best described as a closed "shingle overlap" fashion, the petals being skewed relative to their associated journals to achieve this effect. By the foregoing term, it is meant that each petal has one of its marginal edge portions overlapping and exteriorly outward of (overlying) the marginal edge portion of its neighboring petal on one side thereof, and has its other marginal edge portion overlapping and interiorly inward of (underlying) the marginal edge portion of its neighboring petal on the other side thereof. This arrangement can be easily seen in FIG. 4 wherein an arbitrarily designated center petal 50a is arranged in "shingle overlap" fashion with respect to two other neighboring petals, 50b and 50c. Only three petals of a ring of petals have been shown therein and the frame eliminated, all for the purpose of clarity. Further, the petals are shown in top plan view and a cross-section has been taken along a horizontal plane so that only the base portions and the bearings of the petals are shown. Further, the cover-closed condition of these petals is illustrated in solid lines and should be compared with FIG. 1, and the cover-open position of the petals is shown in dot-and-dash lines and should be compared with FIG. 7. More specifically, the center petal 50a of the three illustrated petals has one of its marginal edge portions 56a overlapping, that is, radially outward of, the adjacent marginal edge portion 54c of its neighboring petal 50c. The center leaf 50a has its other marginal edge portion 54a underlapping, that is, radially inward of, the adjacent marginal edge portion 56b of its neighboring petal 50b. From a comparison of the solid and dot-and-dash positions of FIG. 4 it will be appreciated that the foregoing closed "shingle overlap" placement of the petals is in existence both when the petals are in their cover-closed condition and when the petals are in their cover-open condition, the variance being in the amount (lateral dimension) of overlap between the adjacent marginal portions of neighboring petals.

The manner in which the ring of petals moves from closed to open position will now be apparent. Each of the petals is hinged so as to independently swing inwardly and outwardly on the frame. Each petal is restrained from separate movement inwardly or outwardly by the abutment of its marginal edge portions either against a more outwardly marginal edge portion of one of its neighboring

petals or against the more inwardly marginal edge portion of its other neighboring petal. When it is desired to open the ring of petals, one of the petals is manually outwardly swung by the wearer. Thereupon, one marginal edge portion of said petal urges and moves a more outwardly marginal edge portion of a neighboring petal outwardly, and in turn the said neighboring petal swings outwardly and transmits the same force and movement to its next successive neighbor. This transmission of force and movement continues via each successive petal of the ring of petals until the petal immediately before the first named petal is again reached.

The ring of petals when expanding from its cover-closed position to its cover-open position experiences an increase in maximum diameter (cf. FIGS. 1 and 7).

As the petals move outwardly, the overlapping marginal edge portions experience relative sliding movement along their contacting faces in a circumferential direction away from one another. To facilitate this movement and as well to permit the ring of petals in their closed condition to assume a constricted condition, each petal is slightly offset with respect to its axis of rotation (skewed) so that its inwardly disposed marginal edge portion slopes gradually inwardly while its outwardly disposed marginal edge portion slopes inwardly more severely. As a result and as best seen in FIG. 4, the transverse cross-section of each petal has a progressively smaller radius of curvature in a direction toward its overlapping edge portion.

Although the outwardly biasing force has been described as moving in a circle from one petal to a neighboring overlapping petal, it will be appreciated that said force is transmitted through the ring of petals instantaneously so that as one petal is pulled outwardly manually by the wearer, at the same time all the other petals of the ring of petals swing. Accordingly, the petals seem to unfurl from one another and about the center of the article imitative in a fanciful manner of the unfurling of a flower bud.

It has been found advantageous to provide a definitive contact path between every two overlapping marginal edge portions of adjacent petals. By a contact path is meant a line (or a zone of some minimal area) defined by the successive points of contact between said overlapping marginal edge portions as the cover moves between its open and closed conditions. A definitive contact path is provided so that undesired parts of the petals do not come into contact, which might mar the polished finish which it is desired to give to my article of jewelry and further so that chased portions of the petals do not catch on one another during such movement. In the present embodiment of my invention, the contact path is defined by an elongated rib 66 (see FIG. 5) located on the exterior face of each leaf and running diagonally centrally from the base of the petal along that marginal edge portion 56 which is inwardly disposed of the marginal edge portion of the next neighboring petal and to the adjacent edge 57 of the petal. The exact position of the rib 66 is to be determined, as has been said, by the points of contact between overlapping marginal edge portions of neighboring petals and depends in great part upon the specific shape of the petals. In FIG. 4, it will be seen that the petal 50b carries the rib 66b, while the petal 50a carries the rib 66a. Each rib constitutes a guide path. With the curvilinear cross-section as described above, the petal edges 57 slide along each of the ribs 66 and these ribs are the only points of abutment between any two adjacent petals.

To facilitate the opening of my article of jewelry, a small boss 68 is fixed to the external surface of one of the petals as by soldering in a position in which it is exposed when the cover is closed. The boss has an enlarged head 70 which may be conveniently caught by a fingernail of the wearer.

Means are provided to urge the cover from its open to its closed position so that the cover will be normally closed and so that the cover will return to its closed posi-

tion after it has been opened and released by the wearer. Said means comprises one, and preferably more, as illustrated in the drawings two, coil springs 72. Said springs are located at diametrically opposed positions on the frame 14, each coil spring 72 being located between the legs 38 of an arm, 32 or 34. To accommodate the coil springs, the bearings 60 and an adjacent portion of the bases 52 of two opposed petals 50 are centrally notched as at 74 and each coil spring is wound about the pin 64 and has its ends seated against a petal and the frame in a position to urge said petal inwardly towards said frame (see FIG. 2). The biasing force of the coil springs 72 is transmitted around the ring of petals in a converse manner to that described during the opening movement of the cover. The inclusion of two coil springs has been found to engender a smoother closing movement of the cover. FIG. 2 shows only one spring.

The series of settings 44 on either side of the cover serve as an outward stop for limiting opening movement of the cover and wedging of the overlapping tips of the petals serves as an inward stop for limiting closing movement of the cover.

By virtue of the fact that bases 52 of the petals are quite broad relative to their tips and to the overall dimensions of the cover, view of the display matter (the watch face) within the domed cover is permitted primarily along a viewing axis perpendicular to the plane defined by the bottom rim of the frame. Because the marginal edge portions of the petals overlap along the major portions of their periphery both when closed and when open, the interior of the cover cannot be seen while viewing the article of jewelry in elevation. Thereby, when the wearer desires to ascertain the time of day or look at other display matter within the article of jewelry when he opens the ring of petals, he must peer into the ring of petals from the top in the same manner as if he were looking into a partially opened flower bud. The foregoing further enhances the fanciful imitative nature of my article of jewelry.

40 In conjunction with my article of jewelry, I provide a ring of shimmering stones simulative of the stamens of a flower. To this end and as best seen in FIG. 6, a ring of jewel mounting assemblies 76 is provided each of which includes a pronged setting 78 of the type adapted to grip a gem 80 fancifully representative of an anther. A solid cylindrical elongated shank 82 is fixed to and depends from the setting 78 and terminates in an enlarged spherical lower head 84. The shank 82 is captured in an aperture 86 in the frame, said aperture being of slightly larger diameter than the diameter of the shank 82. A flange 88 extends outwardly from the juncture of the setting 78 and the upper end of the shank 82. The lower end of the aperture 86 has a somewhat enlarged flaring mouth 90 to receive the head 84 and the shank is of sufficient length to permit limited longitudinal movement thereof between stops which constitute the flange 88 on one side and the head 84 on the other side. The radial clearance between the shank and the aperture 86 in the frame and the longitudinal shifting permitted to the shank enable each mounting assembly 76 as a whole to jiggle under the influence of the normal slight movements of the wrist or arm of the wearer. When light plays on the gems 80, the jiggling of the ring of mounting assemblies imparts a shimmering effect. Preferably, numerous mounting assemblies are arranged along the open top rim of the frame 14 and are visible only when the cover is open, thereby encircling the display matter within the cover in a ring of shimmering light. The shimmering ring is not an essential feature of my invention.

70 It thus will be seen that I have provided an article of jewelry with an unfurlable cover which achieves the several objects of my invention and which is well adapted to meet the conditions of practical use.

As various possible embodiments might be made of the 75 above invention, and as various changes might be made

in the embodiment set forth, it is to be understood that all matter herein described or shown in the accompanying drawings is to be interpreted as illustrative and not in a limiting sense.

Having thus described my invention, I claim as new and useful, and desire to secure by Letters Patent:

1. An article of jewelry having an unfurlable cover, said article including a frame having a border defining a plane, a ring of successively marginally overlapping petals, means hinging each of said petals about an axis of rotation on the frame for swinging movement between an inward and outward position, the axes of rotation of the petals lying substantially parallel to said plane and each axis forming with an immediately adjacent axis an interior angle of from about 60° to less than 180° , means for engaging each of said petals successively in order of their positions around said ring for mutual movement of the petals between their closed and open positions whereby the ring of petals is unfurlable from a collapsed condition to an open condition and means biasing the ring of petals towards its collapsed condition.

2. An article of jewelry as set forth in claim 1 wherein display matter is mounted on the frame and the ring of petals in collapsed condition conceals said matter from view and in open condition exhibits said matter to view.

3. An article of jewelry as set forth in claim 2 wherein the lower portions of the petals are broad and overlap in both collapsed and open condition whereby view of the display matter is permitted only along an axis substantially perpendicular to the border plane.

4. An article of jewelry as set forth in claim 1 wherein each of the petals is of outwardly bellied configuration and the tips of the petals in collapsed condition are above the plane of the border so that the ring of petals when collapsed is dome-shaped.

5. An article of jewelry as set forth in claim 4 wherein the interengaging means constitutes the petals with their marginal edge portions arranged in shingle overlap fashion and in a closed pattern.

6. An article of jewelry as set forth in claim 4 wherein each petal has one of its marginal edge portions located radially inwardly of and abuttingly underlapping the marginal edge portion of one of its flanking petals and the other of its marginal edge portions located radially outwardly of and abuttingly overlapping the marginal edge portion of its other flanking petal whereby when one petal is moved outwardly, force and movement is transmitted from the radially inward marginal edge portion of each petal to the overlapping radially outward marginal edge portion of the next successive petal so that overlapping marginal edge portions slide on one another and the ring of petals swing outwardly simultaneously.

7. An article of jewelry as set forth in claim 6 wherein the underlapping one of each set of marginal edge portions carries a guide path defining the points of sliding contact of the said portions.

8. An article of jewelry as set forth in claim 7 wherein the radially inwardly located marginal edge portion of each set of marginal edge portions includes an elongated rib, said rib constituting the guide path.

9. An article of jewelry as set forth in claim 1 wherein the interengaging means constitutes the petals each having a portion underlapping a portion of an adjacent petal, each petal urging the petal it underlaps radially outward when the ring of petals is unfurled from a closed condition to an open condition.

10. An article of jewelry as set forth in claim 1 wherein the biasing means is associated with and urges outwardly at least one but less than all of the petals.

11. An article of jewelry as set forth in claim 1 wherein there is provided a watch located within the cover, wherein said frame has a large through opening and wherein there are provided means rotatably mounting the watch on the frame for rotation about an axis parallel to the plane of the frame opening, rotation of the watch yielding access to the stem of the watch, and means normally retaining the watch in a position with its face exposed when the ring of petals is open.

12. For use with an article of jewelry as set forth in claim 1, a ring of jewel mounting assemblies each including a setting adapted to mount a gem, an elongated shank secured at one end to the setting and an enlarged head secured to the other end of the shank, the shank being located in an elongated oversize aperture in the frame, and the shank being slightly longer than the aperture, the shank being free to move to a limited degree both radially and longitudinally of the aperture whereby when the article of jewelry is worn, the mounting will be jiggled by movement of the wearer and the ring of gems will shimmer.

13. An article of jewelry having an unfurlable cover, said article including a frame having a border defining a plane, a curved line of successively marginally overlapping petals, means hinging each of said petals about an axis of rotation on the frame for swinging movement between an inward and outward position, the axes of rotation of the petals lying substantially parallel to said plane and each axis forming with an immediately adjacent axis an interior angle of from about 60° to less than 180° , means for engaging each of said petals successively in order of their positions along said curved line for mutual movement of the petals between their closed and open positions whereby the curved line of petals is unfurlable from a collapsed condition to an open condition and means biasing the curved line of petals towards its collapsed condition.
